UNITED STATES PATENT OFFICE.

GEORGE BODIN, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed December 26, 1924. Serial No. 758,009.

This invention relates to improvements in mining machines, and more particularly to mining machines of the short wall type in which the operating motor of the machine is disposed at the rear end of the machine frame, and the main operating mechanism including the draft mechanism, and the cutter chain driving mechanism are located in front of the motor and between the latter and the cutter bar.

Machines of this character have further been provided with a retarding drum at the rear end of the motor casing and adapted for attachment with a tail rope, this drum and tail rope being under the control of a suitable retarding means such as a friction brake so as to retard the movement of the rear end of the machine as the flexible feeding devices are operated to move the machine laterally across the working face during the cutting operation.

The principal object of the present invention is to provide an improved form of machine of the class described above in which a driving connection is provided between the operating mechanism at the front of the motor and the tail rope drum at the rear end of the motor, this connection affording means whereby the tail rope drum may at certain times be driven by the motor so as to wind the tail rope thereon and assist in positively moving the machine by means of this tail rope.

I also provide an interlocking connection between the main feed rope drum at the front of the machine and the tail rope drum at the rear end of the machine whereby the power cannot be applied to both drums at the same time.

The invention may be best understood by reference to the accompanying drawings, in which:

Figure 1 is a top plan view of a mining machine constructed in accordance with my invention;

Figure 2 is a fragmentary top plan view of the machine with parts broken away to show the operating mechanism; and

Figure 3 is a sectional view taken on line 3—3 of Figure 2.

In the embodiment illustrated in the drawings the mining machine consists of a cutter arm 10, a frame section 11 and a motor section 12. The cutter arm is of the usual type extending longitudinally from the

front end of the frame section 11. It is also provided with the usual cutter chain (not shown). The motor section 12 consists of a casing 13 wherein is housed a motor comprising an armature 14 and suitable field windings 15 at opposite sides of the casing. The motor is arranged horizontally and longitudinally of the machine frame, the total height thereof including the casing substantially determining the height of the entire machine. The frame 11 is connected forwardly of the motor casing, said frame and motor casing together forming a base plate upon which the machine is moved over the mine floor. The main feed driving mechanism is carried on the frame section and comprises a cable drum 20 arranged on a transverse axis and adjacent one side of the machine. Suitable power connections including speed reducing means are interposed between the rope drum and the motor.

In the form shown this power connection comprises a gear 21, loosely mounted on the hub 20^a of the drum 20, meshed with a pinion 22 on an intermediate shaft 23. The latter shaft is driven through a planetary transmission device indicated generally at 24 and connected through shaft 25 and worm gear 26 to a worm 27 on a longitudinal shaft 28 carrying gear 29 meshed with armature pinion 30. The planetary transmission device may be of any suitable well known form as for instance as shown in patent to C. E. Davis—No. 1,430,799, the details of which need not be herein described excepting to point out a high speed member 31 and a low speed member 32 adapted to be selectively engaged by clutch jaws 33, pinioned to the shaft 23 and movable longitudinally thereof by means of a coaxial shifter arm 37 having laterally extending pins 38 working in slot 39 in said shaft. Through the gearing and power transmission device just described it will be understood that the feed drum 20 may be driven selectively at high and low speed. A cable 40 is wound upon the drum and trained about a suitable guide 41 arranged forwardly of the drum and at the corner of the machine frame in the usual manner. A clutch is interposed between the driving gear 21 and the drum 20, this clutch comprising a clutch member 45 having jaws 46, 46, rotatable therewith and adapted to extend through apertures 47, 47, in the clutch ring 21. When it is de-

sired to engage the clutch, the clutch jaws 46, 46 are projected through and extend beyond the clutch ring 21 into engagement with shoulders 48, 48, carried on the interior 5 of the drum 21 as shown in Figures 2 and 3. The clutch member is shifted laterally by suitable means as for instance a pair of shifter arms 50, 50, connected with a clutch collar 51 on the clutch member 45 and shifted 10 by means of a yoke 52 and shifting lever 53 pivoted at 55. The entire clutch mechanism at one end of the drum is enclosed by a housing 54.

A tail rope drum 60 is rotatably mounted 15 on a shaft 61 at the rear end of the motor casing, this shaft extending rearwardly on a horizontal axis so that the tail rope 62 may extend laterally from the machine and be anchored in a suitable position to control the angular position of the machine to the working face during the cutting operation. The drum 60 is provided with a brake band 63 controllable by a tension control member 64 of the usual type.

20 Referring now to the power connection between the feed operating mechanism and the tail rope drum 60 it will be observed that I provide a longitudinal shaft 70 arranged along the lower side of the motor casing 13 and at the rear of the feed operating drum 20. This shaft is provided at its forward end with a bevel pinion 71 meshing with a similar pinion 72 keyed on the spur shaft 73. A spur pinion 74 is also keyed upon this shaft and is engaged with the driving gear 22 on the main driving shaft 23. The rear end of the shaft 70 is provided with a pinion 75 meshed with a spur gear 76 keyed on the periphery of the 25 tail rope drum 60. A clutch member 77 is feathered on the rear end of the shaft 70 and is provided with clutch jaws 78 adapted to engage with coacting clutch jaws 79 carried on the face of pinion 75. The clutch member 77 is controlled by a lever 80 pivoted on a support 81 and having a shifter yoke 82 having pins 83 riding in an annular groove 84 in the member 77. By means of this clutch and shifting mechanism 30 the shaft 70 may be engaged with or disengaged from the pinion 75 so as to drive the tail rope drum 60 or allow it to rotate under control of a friction band 63 in the usual manner.

35 I also provide an interlocking connection between the clutch members controlling the main feed rope drum 20 and the tail rope drum 60, this interlocking connection being arranged so that only one of the drums 40 may be driven at one time. This arrangement is advantageous in a machine of this character inasmuch as the head and tail ropes, connected with these two drums, extend in opposite directions from the machine, so that an accidental simultaneous

application of power to both drums would be likely to cause serious damage not only to the machine but to the operator. This interlocking mechanism as shown herein comprises a lever 90 rocking on fulcrum 91 70 at the rear end of the motor casing and connected to the lever 80 by a link 92. A rod 93 extends forwardly from the upper end of the lever 90 and is pivoted to a bell crank lever 94 pivoted on a vertically disposed bearing pin 95 and having its free arm 96 engaging the upper end of the shifter lever 53 which operates the clutch member 45. By means of this interlocking operating mechanism it will be seen that either one 75 of the drums may be driven but when one drum is connected the other is disconnected. In the position of the operating levers shown in the drawings in Figure 3, the two 80 clutches are in neutral position so that neither of the drums are being driven. It will be clearly seen however that by moving the lever 80 forwardly, the clutch member 77 will be withdrawn rearwardly and removed still further from the coacting clutch 85 jaws 79 of the gear 75. This same movement of the lever will rock the lever 90 and draw rod 93 rearwardly, and cause the upper end of the lever 53 to rock outwardly and the lower end thereof carrying the 90 shifter yoke and shifter members 50 inwardly to engage the clutch jaws 47 with coacting members 48 within the feed rope drum 20, thus forming a driving connection between the motor and the feed operating 95 drum. The reverse movement of the handle 80 will move the clutch member through the neutral position shown in Figure 3 and into position where the clutch member 77 engages the gear pinion 75 while the clutch 100 operating lever 53 is swung in the opposite direction to withdraw the clutch member 45 from engagement with clutch members 48.

105 Either of the drums may be rotated in either direction as desired by reversing the direction of the rotation of the motor in the usual manner.

110 While I have shown and described one embodiment of my invention it will be understood that the arrangement and construction of the parts may be altered without departing from the spirit and scope thereof. Furthermore, I do not wish to be construed as limiting myself to the particular construction illustrated excepting as it 115 may be specifically limited in the appended claims.

120 I claim as my invention:

1. In a mining machine, a motor, a forwardly projecting cutter bar and flexible feed driving mechanism including a feed drum and a multiple speed transmission device, both said cutter bar and feed mechanism being disposed in front of said motor 125

- and included substantially within the vertical limits thereof, a tail rope drum rotatable on an axis extending longitudinally of the machine and at the rear end of said 5 motor, power connections between said tail rope drum and said multiple speed transmission device including a shaft extending along one side of said motor casing, and means for selectively actuating either said feed drum or said tail rope drum through said multiple speed transmission device at a plurality of feeding speeds.
2. In a mining machine having a motor casing, feed driving mechanism arranged 15 forwardly of said motor casing and substantially within the vertical limits thereof, said feed driving mechanism including a rotating drum and clutch mechanism for connecting or disconnecting said drum from 20 said feed driving mechanism, a tail rope drum rotatable on an axis extending longitudinally of the machine and at the rear end of said motor casing, power connections between said feed operating mechanism 25 and said tail rope drum including a shaft extending along one side of said motor casing, clutch means for connecting or disconnecting said tail rope drum from said shaft, and an interlocking mechanism connecting 30 the clutch members of the feed drum and tail rope drum respectively operative to engage one of said clutches while the other is disengaged.
3. In a mining machine having a motor casing, feed driving mechanism arranged 35 forwardly of said motor casing and substantially within the vertical limits thereof, said feed driving mechanism including a rotating drum and clutch mechanism for connecting or disconnecting said drum from 40 said feed driving mechanism, a tail rope drum rotatable on an axis extending longitudinally of the machine and at the rear end of said motor casing, power connections be- 45 tween said feed operating mechanism and said tail rope drum including a shaft ex-
- tending along one side of said motor casing, clutch means for connecting or disconnecting said tail rope drum from said shaft, an interlocking mechanism connecting the 50 clutch members of the feed drum and tail rope drum respectively operative to engage one of said clutches while the other is disengaged, and clutch operating mechanism for controlling said interlocking mechanism 55 mounted on the rear end of the motor casing.
4. In a mining machine, a motor, a forwardly projecting cutter bar and flexible feed driving mechanism, both said cutter bar and feed mechanisms being disposed in front 60 of said motor and included substantially within the vertical limits thereof, a tail rope drum rotatable on an axis extending longitudinally of the machine and at the rear end of said motor, power connections 65 between said tail rope drum and said feed driving mechanism including a shaft extending along one side of said motor casing, and means for selectively actuating either 70 said feed drum or said tail rope drum independently of each other.
5. In a mining machine, a motor, a forwardly projecting cutter bar and flexible feed driving mechanism including a feed drum rotatable on a transverse axis and disposed on the advancing side of said cutter bar, both said cutter bar and feed mechanism being disposed in front of said motor and included substantially within the vertical limits thereof, a tail rope drum rotatable 75 on an axis extending longitudinally of the machine and at the rear end of said motor, power connections between said tail rope drum and said feed driving mechanism including a shaft extending along one side 80 of said motor casing, and means for selectively actuating either said feed drum or said tail rope drum.
